(57) **CLAIM**

The ornamental design of a combination illumination device and power system, as shown and described.

DESCRIPTION

FIG. 1 is a perspective view of the top, front, and right side of a combination illumination device and power system showing an embodiment of the new design.

FIG. 2 is a front view thereof.

FIG. 3 is a back view thereof.

FIG. 4 is a left view thereof.

FIG. 5 is a right view thereof.

FIG. 6 is a top view thereof; and,

FIG. 7 is a bottom view thereof.

The broken lines show portions of the article that form no part of the claimed design.

1 Claim, 7 Drawing Sheets
